UNITED STATES PATENT OFFICE.

WILLARD F. RICHARDS, OF DEPEW, NEW YORK, ASSIGNOR TO GOULD COUPLE COMPANY, OF NEW YORK, N. Y.

RAILWAY-CAR TRUCK.

1,081,406.

Specification of Letters Patent. Patented Dec. 16, 1913.

Application filed December 19, 1912. Serial No. 737,591.

To all whom it may concern:

Be it known that I, WILLARD F. RICHARDS, a citizen of the United States, residing at Depew, in the county of Erie and State of New York, have invented a new and useful Improvement in Railway-Car Trucks, of which the following is a specification.

This invention relates to car truck side frames, and more particularly to means for securing the journal boxes to side frames of that kind, now well known, which are provided at their opposite ends with integral depending jaws or parts that straddle and hold the journal boxes in place in such a manner that the journal boxes, together with the car wheels and axles, can be readily removed from the truck by raising or jacking up the side frames. Retaining means of some sort are ordinarily provided for preventing the accidental dropping of the journal boxes from between the frame jaws which might otherwise happen, for example, if the truck left the track from any cause.

The objects of this invention are to produce strong and reliable devices for retaining the journal boxes in the jaws, which are of a novel construction adapted to be readily operated to secure and release the journal boxes and have means for releasably holding them in their operative position; also to improve the construction of devices of this kind in the respects hereinafter specified.

In the accompanying drawings: Figure 1 is a fragmentary side elevation, partly in section on line 1—1, Fig. 2, of a car truck embodying the invention. Fig. 2 is a plan view thereof, partly in section on line 2—2, Fig. 1. Fig. 3 is an end elevation thereof. Like reference characters refer to like parts in the several figures.

A represents the metal side frame of a car truck which is provided at each end with integral depending portions *a a'* forming rigid jaws between which a journal box B is held. Except as hereinafter described, the side frame may be of any suitable construction but preferably consists of steel casting of the form shown in the drawings. The side walls of the journal box are provided at their outer faces with ribs *b*, between which the depending jaws *a a'* of the side frame are adapted to enter for holding the journal box from lateral movement relatively to the frame. Preferably the de-

pending jaws *a a'* of the side frame do not extend downwardly to the full depth of the journal box, so that the side frame need not be raised or jacked up so high as would otherwise be necessary to permit the journal box to be slipped downwardly out of engagement with the jaws, thus greatly facilitating the removal of the journal boxes, axles and wheels from the car truck. All of these parts, in as far as above described, are of well known construction.

The means employed for retaining the journal boxes in place in the side frames are constructed as follows: The depending jaws *a a'* of the side frame are provided with pockets or recesses C which have open sides facing the journal box and in which the holding devices for the journal box are located. Each of these holding devices consists of an arm or block D which is pivoted in the pocket, preferably by a pivot shaft or pin *d* driven through a hole in the arm and adapted to turn in holes in the side walls of the pocket. This arm is adapted to be swung into and out of a recess E formed in the side of the journal box and to bear on a shoulder *e* at the upper edge of the recess for holding the box in place. The pivot shaft *d* is provided with a suitable part, such as a square end *d'* located outside the side frame, adapted to be engaged by a suitable tool for turning the shaft to move the arm D into and out of its holding position.

The arm or block D is preferably provided with means for retaining it in its holding position. In the construction shown for this purpose, the arm or block is made with an end socket and contains a plunger F, which is pressed outwardly by a spring *f* located within the socket under the plunger. The end of the plunger is adapted to engage or seat in a depression *f'* formed in the shoulder *e* of the journal box for releasably retaining the holding arm in position to hold the box within the jaws of the side frame. When the shaft *d* is turned to move the arm D out of its holding position, the plunger is forced into the hollow end of the arm by the wedging action of the inclined faces of the groove and the end of the plunger. The arm or block D could be pivoted in the pocket and actuated in other suitable ways, and means of different construction could be employed for releasably

holding the arm or block in its operative holding position.

The recesses E formed in the outer faces of the side walls of the journal boxes coincide with the usual lugs G provided interiorly on the side walls of the box for retaining the journal brasses in position, so that by forming the recesses E in this manner, a saving in metal is effected, making 10 the box lighter in weight and at the same time providing means whereby the box can be held on the side frame.

Holding means of the described construction are reliable and effective in operation, 15 since the arm D will be retained in its inclined or holding position by gravity, as well as by the engagement of the spring plunger F in the groove f'. The downward pressure of the journal box B on the arms D, 20 due to the weight of the box, wheels and axle, will also tend to move the arms D into tighter engagement with the box. When the arm is in its vertical position, out of engagement with the journal box, as indicated 25 by dotted lines in Fig. 1, the friction of the plunger against the upper wall of the recess C will hold the arm in this position.

I claim as my invention:

1. A car truck side frame having jaws 30 adapted to straddle a journal box, a shoulder formed on the journal box, and an arm pivoted on the side frame and adapted to be swung into engagement with said shoulder to retain the journal box between said 35 jaws, substantially as set forth.

2. A car truck side frame having jaws adapted to straddle a journal box, one of 40 which jaws has a pocket, the open side of which faces the journal box, a shoulder formed on the journal box, and an arm pivotally mounted in said pocket and adapted to be swung into engagement with said shoulder to retain the journal box between the jaws, substantially as set forth.

45 3. The combination of a car truck side frame having jaws, a journal box adapted to be held between said jaws and having an inwardly extending projection and a recess in the outer face of the journal box coinciding with said projection, and locking means 50

pivoted on said side frame and adapted to be swung into said recess for holding the journal box in place between the jaws, substantially as set forth.

4. A car truck side frame having jaws 55 adapted to straddle a journal box, a shoulder formed on the journal box, an arm pivoted on the side frame and adapted to be swung into engagement with said shoulder to retain the journal box between said jaws, 60 and means for retaining said arm in holding engagement with said journal box, substantially as set forth.

5. A car truck side frame having jaws adapted to straddle a journal box, a shoulder 65 formed on the journal box, an arm pivoted on the side frame and adapted to be swung into engagement with said shoulder to retain the journal box between said jaws, and a retaining member mounted on said 70 arm and adapted to be pressed into engagement with said journal box for releasably holding the arm in its holding position, substantially as set forth.

6. A car truck side frame having jaws 75 adapted to straddle a journal box, a shoulder formed on the journal box and having a groove, an arm pivoted on the side frame and adapted to swing into engagement with said shoulder, and a spring-pressed plunger 80 mounted to slide lengthwise of the arm and adapted to engage in said groove for yieldingly holding the arm in its holding position, substantially as set forth.

7. A car truck side frame having jaws 85 adapted to straddle a journal box, one of which jaws has a pocket, the open side of which faces the journal box, a shoulder formed on the journal box, a locking arm in 90 said pocket adapted to engage said shoulder on the journal box, and a pivot shaft for said locking arm, the end of the shaft being shaped to engage with a tool for turning the same, substantially as set forth.

Witness my hand, this 13th day of December, 1912.

WILLARD F. RICHARDS.
